UNITED STATES PATENT OFFICE.

WILLIAM T. SHERMAN, OF TROY, NEW YORK, ASSIGNOR TO HENRY L. HUGHES CO., INC., OF NEW YORK, N. Y., A CORPORATION OF NEW YORK.

BRUSH-MAKING MACHINE.

Application filed December 30, 1919. Serial No. 348,334.

To all whom it may concern:

Be it known that I, WILLIAM T. SHERMAN, a citizen of the United States, residing at Troy, in the county of Rensselaer and 5 State of New York, have invented new and useful Improvements in Brush-Making Machines, of which the following is a specification.

Reference may be had to the accompanying drawings, and the reference characters marked thereon, which form a part of this specification. Similar characters refer to similar parts in the several figures therein.

This invention relates more particularly 15 to machines for the manufacture of bristle supporting rubber pads suitable for hair brushes and the like.

In such pads the bristles are inserted 20 separately or in groups of two or more through small apertures in the pad, the inner ends of the bristles being provided with heads or offsets which are covered in some suitable manner with a backing-sheet whereby the bristles are permanently mounted in 25 the rubber pad.

In United States Letters Patent No. 1,324,178, granted to me December 9, 1919, 30 I have shown and described the manner in which such a pad is filled with bristles, and reference may be had to said Letters Patent for a more complete understanding of the nature and objects of the present invention. As shown in said Letters Patent the insertion of the bristles into the holes in the 35 rubber pad is facilitated by first forcing a tube through each hole in the pad and then inserting the bristles through the tubes, after which the tubes are withdrawn from the pad, leaving the bristles occupying the 40 respective holes in the pad.

It is of course desirable that the holes in the pad should be as small as possible in order to tightly engage the inserted bristles; and obviously as the tubes are necessarily of 45 larger diameter than the bristles, considerable resistance is offered to the forcing of the tubes through the respective holes in the pad.

The principal object of the present invention is to facilitate the insertion of the tubes 50 through the rubber pad.

I have ascertained and demonstrated that the insertion of the tubes through the pad can be greatly facilitated by first forcing

through the respective holes in the pad, 55 pins of a size adapted to enter the respective tubes and then forcing the tubes over the respective pins and through the respective apertures in the pad, after which the pins can be withdrawn leaving the tubes inserted 60 through the pad.

Other objects of the invention will appear in connection with the following description.

Fig. 1 of the drawings is a view in side 65 elevation of a press-mechanism which comprises part of my invention.

Fig. 2 is a view in front elevation of the same with the handle partly broken away.

Fig. 3 is a horizontal section of the same 70 taken on the broken line 3—3 in Figs. 1 and 2.

Fig. 4 is a plan view of a broken-away portion of the bed of the press and the 75 mechanism mounted thereon.

Fig. 5 is a central vertical longitudinal section of a broken-away head portion of the press taken on the broken line 5—5 in Fig. 2.

Fig. 6 is a vertical cross-section of the 80 same taken on the broken line 6—6 in Fig. 5.

Fig. 7 is a view in cross-section of one of the rubber pads.

Fig. 8 is a similar view of a tube-plate 85 having tubes adapted to be inserted through the respective apertures in said pad.

Fig. 9 is a similar view of the guide-and-stripper-plate.

Fig. 9^a is a similar view showing the rubber 90 pad mounted upon the guide-and-stripper-plate.

Fig. 10 is a cross-section taken on the broken line 10—10 in Fig. 4, through the base of the press and the mechanisms 95 mounted thereon.

Fig. 11 is a similar view showing the guide-and-stripper-plate with the rubber 100 pad mounted thereon impaled upon the pins by the first operation of the press.

Fig. 12 is a similar view illustrating the manner in which the tubes are guided upon the pins by the guide-and-stripper-plate, in position to be forced through the rubber pad.

Fig. 13 is a similar view showing the tubes 105 fully inserted through the pad while the pins still remain within the tubes.

Fig. 14 is a similar view showing the tube-supporting plate and the guide-and-stripper-plate, and the rubber pad mounted upon the tubes.

5 Referring to the drawings wherein the invention is shown in preferred form, 1 is a pad or sheet of soft vulcanized rubber having numerous small perforations, 2, each adapted to receive a single bristle or a group 10 of two or more bristles as may be desired.

These perforations, 2, are of very small diameter adapted to closely fit and elastically embrace the bristle or bristles inserted therethrough.

15 3 is a tube-carrying plate, having projecting tubes, 4, corresponding in arrangement with the respective perforations, 2, in the rubber pad, 1, which tubes are to be forced through the respective perforations, 2, in the 20 rubber pad.

15 3 is a tube-carrying plate, having projecting tubes, 4, corresponding in arrangement with the respective perforations, 2, in the rubber pad, 1, which tubes are to be forced through the respective perforations, 2, in the 25 rubber pad.

The guide-and-stripper-plate, 5, is provided with holes, 5^a, corresponding in number and location with the holes, 2, in the rubber pad, and with the tubes, 4, in the 25 tube-plate, 3.

These holes, 5^a, in the guide-and-stripper-plate are, adjacent to the under surface of the plate, severally of a diameter adapted to receive the respective tubes, 4, while the portion of each hole adjacent to the upper side of the plate is flared to more freely receive these tubes, 4, so as to guide the tubes into the cylindrical portions of the respective openings.

35 The guide-and-stripper-plate has a pair of gage-pins, 5^b, projecting from its underside upon which the rubber pad, 1, can be impaled, the rubber pad being provided with similarly located openings, 2^a, adapted to 40 receive the respective gage-pins with the axes of the openings, 2, alined with the respective axes of the openings, 5^a, in the guide-and-stripper-plate.

In addition to this guiding function of 45 the plate, 5, it serves as a convenient means for stripping the rubber pad off from the tubes after the function of the tubes has been accomplished in the inserting of the bristles through the pad.

50 In carrying out my invention in its preferred form, I employ a press having a base or bed, 6, and a movable member, 7, adapted to be moved toward and from the bed by means of a toggle-joint, 8, the upper member, 55 of which has a projecting handle, 9, whereby the press may be operated.

The base, 6, of the press has on its upper side a pair of undercut-slideways, 10, adapted to receive a slide-plate, 11, removably held in position upon the bed by means of latches, 12.

Formed as a part of or fixedly mounted upon the slide-plate, 11, is a pin-supporting plate, 13, having pins, 14, projecting upwardly therefrom, corresponding in number

and arrangement with the tubes, 4, and the perforations, 2, in the rubber pad, 1. Also forming part of or fixedly mounted upon the slide-plate, 11, is a pad-supporting plate, 15, provided with tube-receiving perforations, 16, corresponding in number and arrangement with the tubes, 4, and through which perforations, 16, the respective pins, 14, project above the pad-supporting surface of the plate, 15.

75 A plurality of guide-pins, 17, project upwardly from the pin-supporting plate, 13, adapted to enter correspondingly located openings, 18, in the tube-carrying plate, 3, and guide-and-stripper-plate, 5, whereby 80 said tube-supporting plate, and said guide-and-stripper-plate are movably supported in the path of the movable member, 7, of the press, and the pins, 14, are caused to enter the respective tubes, 4, as the tube-carrying 85 plate is forced by the movable member, 7, of the press toward the base, 6, of the press, with the tubes entered within the flared ends of the respective openings, 5^a, in the guide-and-stripper-plate.

90 The operation of the apparatus is as follows:

The rubber pad, 1, is impaled upon the pins, 5^b, of the guide-and-stripper-plate, 5, thus locating the perforations, 2, in the rubber pad in alinement with the axes of the respective openings, 5^a, in the guide-and-stripper plate. The movable member, 7, of the press being raised, the guide-and-stripper-plate, 5, having the rubber pad thus 100 mounted upon its underside, is applied to the guide-pins, 17, thus bringing into axial alinement the pins, 14, with the respective openings, 2, in the rubber pad and the respective openings, 5^a, in the guide-and-stripper-plate.

105 The guide-and-stripper-plate is then forced downward by the downward movement of the movable member, 7, of the press caused by operating the handle, 9, thus impaling the rubber pad, 1, upon the pins, 14, with the upper ends of said pins passing within the cylindrical portions of the respective openings, 5^a, in the guide-and-stripper-plate as shown in Fig. 11. The movable 110 member, 7, of the press is then raised and the tube-plate, 3, is applied to the guide-pins, 17, thus bringing its downwardly projecting tubes into substantial alinement with the openings, 5^a, in the guide-and-stripper-plate.

115 The movable member, 7, of the press is then again forced downward causing the lower ends of the tubes, 4, to enter the flared ends of the respective openings, 5^a, in the guide-and-stripper-plate whereby the respective tubes are guided and centered with respect to the cylindrical portions of said openings, 5^a, and thus caused to receive the upper ends of the respective pins, 14.

120 The final downward movement of the mova- 130

ble member, 7, of the press further depresses the tube-plate, 3, forcing the tubes downward over the respective pins, 14, and thus causing them to be forced through the respective perforations, 2, in the rubber pad, the rubber pad being supported against downward movement by the pad-supporting plate, 15, through the perforations, 16, in which, however, the respective tubes freely pass.

At the completion of this operation the parts are in the respective positions shown in Fig. 13, and when the movable member, 7, of the press is raised, the tube-carrying plate, 3, with the stripper-plate, 5, applied thereto and the rubber pad, 1, impaled upon the tubes, 4, can be withdrawn from the press, the tubes, 4, withdrawing easily from the pins, 14.

The relative positions of said plates and the rubber pad and tubes are shown in Fig. 14.

The tubes are thus threaded through the respective perforations, 2, in the rubber pad ready for the insertion of the bristles in the manner shown in my said prior patent or in any other desired manner.

To facilitate removing the assembled tube-carrying plate, 3, stripper-plate, 5, and rubber pad, 1, from the press, I have shown a pair of hooks, 19, movably mounted on the movable member, 7, of the press which hooks are adapted to underlyingly engage the tube-carrying plate, 3, or the stripper-plate, 5, when said plates are at the limit of their downward movement caused by the downward movement of the movable member, 7, of the press.

These hooks are moved in one direction by means of coil-springs, 20, and in the opposite direction by means of a cam, 21, actuated by a handle, 22, to force slide pins 23, against the upper ends of the hooks, 19, which hooks are in the form of levers pivoted at 24, upon the movable member, 7, of the press.

After the movable member, 7, of the press has been forced to the limit of its downward movement, the hooks, 19, are forced into engagement with the plate, 3, or with the plate, 5, by operating the cam, 21, so that said plates with the rubber pad impaled upon the tubes, 4, are withdrawn from the pins, 14, by the upward movement of the member, 7.

The cam, 21, being then operated in the reverse direction permits the hooks to be withdrawn due to the action of the springs, 20, thus releasing the tube-carrying plate, 60 stripper-plate and rubber pad for removal from the press.

Any other known means may be substituted for the hooks, 19, as a means for withdrawing from the pins the rubber pad impaled upon the tubes, 4.

Any desired number of tubes, 4, may be employed in accordance with the character of the work being done.

I have shown and described my invention in its preferred application to a rubber pad 70 in making brushes of the kind above described and referred to in my said prior patent, but it will be obvious that my invention is for certain purposes applicable to the insertion of tubes through flexible or 75 elastic material of various kinds and for various purposes.

What I claim as new and desire to secure by Letters Patent is—

1. A device of the class described having 80 a pad-supporting surface provided with a tube-receiving opening and having a pin projecting through said opening beyond said pad-supporting surface, and a tube opposed to said pin and movable thereover into said 85 opening and withdrawable from said pin.

2. In an apparatus of the class described and in combination, a pin-supporting member having a pad-supporting surface provided with an opening; a pin projecting 90 through said opening beyond said pad-supporting surface; and a tube-carrying plate having a projecting tube opposed to and adapted to pass over said pin and into said opening in said pad-supporting surface, and withdrawable from said pin. 95

3. In an apparatus of the class described and in combination, a pin-supporting member having a pad-supporting surface provided with an opening; a pin projecting 100 through said opening beyond said pad-supporting surface; and a tube-carrying plate having a projecting tube adapted to pass over said pin and into said opening in said pad-supporting surface; and a stripper-plate 105 provided with an opening adapted to receive said tube.

4. In an apparatus of the class described and in combination, a pin-supporting member having a pad-supporting surface provided with tube-receiving openings; pins projecting through the respective openings beyond said pad-supporting surface; a tube-carrying plate having projecting tubes arranged to correspond with the respective 115 pins; and guiding mechanism whereby the pins are caused to enter the respective tubes as the tube-carrying plate is moved toward the pin-supporting member. 120

5. In an apparatus of the class described and in combination, a pin-supporting member having a pad-supporting surface provided with tube-receiving openings; pins projecting through the respective openings beyond said pad-supporting surface; a tube-carrying plate having projecting tubes arranged to correspond with the respective pins; guiding mechanism whereby the pins are caused to enter the respective tubes as the tube-carrying plate is moved toward the 130

pin-supporting member; and a stripper-plate provided with openings for the respective tubes.

6. In an apparatus of the class described and in combination, a press having a bed, a member movable toward and from the bed, and means for moving said movable member; a pin-supporting member mounted upon said bed and having a pad-supporting surface provided with tube-receiving openings; pins projecting through the respective openings beyond said pad-supporting surface; a tube-carrying plate having projecting tubes arranged to correspond with the respective pins; and guiding mechanism whereby said tube-supporting plate is movably supported in the path of said movable member of the press with the tubes in alinement with the respective pins.

7. In an apparatus of the class described and in combination, a press having a bed, a member movable toward and from the bed, and means for moving said movable member; a pin-supporting member mounted upon said bed and having a pad-supporting surface provided with tube-receiving openings; pins projecting through the respective openings beyond said pad-supporting surface; a tube-carrying plate having projecting tubes arranged to correspond with the respective pins; guiding mechanism whereby said tube-supporting plate is movably supported in the path of said movable member of the press with the tubes in alinement with the respective pins; and a stripper-plate provided with openings for the respective tubes.

8. In an apparatus of the class described and in combination, a press having a bed, and a member movable toward and from the bed, and means for moving said movable member; a pin-supporting member mounted upon said bed and having a pad-supporting surface provided with tube-receiving openings; pins projecting through the respective openings beyond said pad-supporting surface; a tube-carrying plate having projecting tubes arranged to correspond with the respective pins when the plate is located in the path of said movable member of the press; and tube-plate-engaging hooks carried by said movable member of the press for withdrawing the tube plate and tubes from the pins.

55 9. In an apparatus of the class described
and in combination, a press having a bed,
a member movable toward and from the bed,
and means for moving said movable mem-
ber; a pin-supporting member mounted
60 upon said bed and having a pad-supporting
surface provided with tube-receiving open-
ings; pins projecting through the respective
openings beyond said pad-supporting sur-
face; a tube-carrying plate having project-
65 ing tubes arranged to correspond with the

respective pins; guiding mechanism whereby said tube-supporting plate is movably supported in the path of said movable member of the press with the tubes in alignment with the respective pins; and tube-plate-engaging hooks carried by said movable member of the press for withdrawing the tube-plate and tubes from the pins. 70

10. In an apparatus of the class described and in combination, a press having a bed, a member movable toward and from the bed, and means for moving said movable member; a pin-supporting member mounted upon said bed and having a pad-supporting surface provided with tube-receiving openings; pins projecting through the respective openings beyond said pad-supporting surface; a tube-carrying plate having projecting tubes arranged to correspond with the respective pins; guiding mechanism whereby said tube-supporting plate is movably supported in the path of said movable member of the press with the tubes in alignment with the respective pins; hooks movably mounted upon said movable member of the press; and mechanism including a hand-operated member for moving said hooks into and out of engagement with the tube-carrying plate. 75 80 85 90 95

11. In an apparatus of the class described 95
and in combination, a pin-supporting mem-
ber having a pad-supporting surface pro-
vided with openings; pins projecting
through the respective openings beyond said
pad-supporting surface; a tube-carrying 100
plate having tubes adapted to pass over the
respective pins and into the respective open-
ings in said pad-supporting surface; and a
guide-plate provided with openings there-
through, said openings adjacent to the un- 105
derside of said plate being adapted to freely
receive the respective pins and to closely
receive the respective tubes, said openings
being flared toward the upper side of said
plate. 110

12. In an apparatus of the class described and in combination, a pin-supporting member having a pad-supporting surface provided with tube-receiving openings; pins projecting through the respective openings beyond said pad-supporting surface; a tube-carrying plate having projecting tubes arranged to correspond with the respective pins; and a guide-plate provided with tube-receiving openings arranged to correspond with the respective pins and tubes, and having on its underside gage-pins adapted to engage similarly located gage-openings in a pad provided with openings corresponding in arrangement with those in said guide-plate. 115 120 125

13. In an apparatus of the class described and in combination, a pin-supporting member having a pad-supporting surface provided with tube-receiving openings; pins 130

- projecting through the respective openings beyond said pad-supporting surface; a tube-carrying plate having projecting tubes arranged to correspond with the respective pins; and a guide-plate provided with tube-receiving openings arranged to correspond with the respective pins and tubes, and having on its underside gage-pins adapted to engage similarly located gage-openings in a 5 pad provided with openings corresponding in arrangement with those in said guide-plate; and guiding means mounted upon said pin-supporting member for guiding said guide-plate and tube-carrying plate toward the pins on the pin-supporting member.
- 10 14. In an apparatus of the class described and in combination, a pin-supporting member having a pad-supporting surface provided with tube-receiving openings; pins
- projecting through the respective openings beyond said pad-supporting surface; a tube-carrying plate having projecting tubes arranged to correspond with the respective pins; a guide-plate provided with tube-receiving openings arranged to correspond with the respective pins and tubes, and having on its underside gage-pins adapted to engage similarly located gage-openings in a 25 pad provided with openings corresponding in arrangement with those in said guide-plate, said openings in the guide-plate adjacent to the underside thereof being adapted to freely receive the respective pins and to closely receive the respective tubes, said 30 openings being flared toward the upper side of said plate.
- 20 In testimony whereof I have hereunto set my hand this 13th day of December, 1919.

WILLIAM T. SHERMAN.
